UNITED STATES PATENT OFFICE.

LEVIN H. CLOGG, OF PHILADELPHIA, PENNSYLVANIA.

DESIGN FOR A TIP-CUP FOR UMBRELLAS.

SPECIFICATION forming part of Design No 20,276, dated November 11, 1890.

Application filed June 27, 1890. Serial No. 357,006. Term of patent 3½ years.

To all whom it may concern:

Be it known that I, LEVIN H. CLOGG, a citizen of the United States, residing in the city of Philadelphia and State of Pennsylvania, 5 have invented a new and original Design for Tip-Cups for Umbrellas and Parasols, of which the following is a clear and sufficient specification, reference being had to the photograph annexed to the same.

10 My design is clearly shown in the accompanying drawing; and it consists, essentially, of a cylinder having annular projections formed of flat slanting surfaces thereon, said

cylindrical surfaces being smooth and plain, and said slanting surfaces having a roughened or broken surface. 15

I claim—

The design for a tip-cup, substantially as shown and described.

In token whereof I have hereto set my hand 20 this 25th day of June, 1890.

LEVIN H. CLOGG.
